United States Patent

Des. 240,970
Patented Aug. 17, 1976

240,970

WELDER'S MASK

Raymond D. Barta, Oakland, Mich., assignor to
Airco, Inc., Montvale, N.J.

Filed Sept. 26, 1974, Ser. No. 509,522

Term of patent 14 years

Int. Cl. D2—03

U.S. Cl. D2—232

FIG. 1

FIG. 2

FIG. 1 is a front and side perspective view of a welder's mask showing my new design; and

FIG. 2 is a perspective view of the rear thereof.

I claim:

The new and ornamental design for a welder's mask, substantially as shown and described.
